UNITED STATES PATENT OFFICE.

JOHN SAMUEL MARTIN, OF ATLANTIC CITY, NEW JERSEY, ASSIGNOR TO SPLITDORF ELECTRICAL COMPANY, OF NEWARK, NEW JERSEY.

MAGNETO ATTACHMENT.

1,318,218.

Specification of Letters Patent.

Patented Oct. 7, 1919.

Application filed January 16, 1915. Serial No. 2,625.

To all whom it may concern:

Be it known that I, JOHN S. MARTIN, a citizen of the United States, and a resident of Atlantic City, in the county of Atlantic 5 and State of New Jersey, have invented a new and Improved Magneto Attachment, of which the following is a full, clear, and exact description.

My invention relates to attachments for 10 high-tension magnetos of internal-combustion engines whereby to the shaft of the magneto can be given an accelerated movement while the engine is started, thereby creating a spark substantially equal to the 15 spark created during the normal running speed of the engine shaft.

An object of the invention is to provide 20 an attachment of the class described which is simple, strong, and inexpensive, which has no binding screws, and in which all the parts are so inclosed that none can get out of order, and consequently for which attachment very little attention is necessary.

A further object of the invention is to provide 25 an attachment of the class described in which normally the magneto shaft is unyieldingly coupled to the mechanism driving it so that no lagging of the magneto shaft can take place at high speed of the engine.

30 A still further object of the invention is to provide an attachment of the class described which will automatically become inoperative as the spark control of the magneto is advanced.

35 With the above and other objects in view, the nature of which will more fully appear as the description proceeds, the invention consists in the novel construction, combination and arrangement of parts as herein 40 fully described, illustrated and claimed. In the accompanying drawings, forming part of the application, similar characters of reference indicate corresponding parts in all the views, and

45 Figure 1 is a side elevation of a magneto provided with my attachment;

Fig. 2 is a front elevation of my attachment on the magneto;

Fig. 3 is an axial section therethrough 50 on line 3-3, Fig. 4;

Fig. 4 is a vertical section on line 4-4, Fig. 3;

Fig. 5 is a horizontal, axial section on line 5-5, Fig. 4;

Fig. 6 is the inside elevation of a driving member;

Fig. 7 is a side elevation of the attachment alone as it appears on the shaft of the magneto; and

Fig. 8 is a perspective view of the key which normally couples the driving and the driven members.

Referring to the drawings, the magneto shaft 9 has attached thereto a driven member 10 so that the same is constrained to participate in the movement of the driven member. The driven member 10 is provided with an annular recess 11 accessible from the front of said member, and which annular recess 11 is bridged at 12 by a portion preferably forming an integral part of the driven member. Contacting with the front of the driven member is a driving member 13 in the shape of a disk centrally apertured. The aperture engages a reduced portion 14 at the front of the driven member whereon said driving member is free to turn and is maintained concentric with the driven member. The disk has a lateral lug 15 which projects into the recess 11 and is normally maintained against the bridge portion 12 by a resilient member 16, preferably a coil spring, one end of which engages the bridge 12 and the other the lug 15.

The lateral surface of the driven member 10 is preferably depressed so that a marginal flange 17 is formed at the rear end of the driven member. The said depressed lateral surface of the driven member has keyways 18 running parallel to the axis of the driven member and which are diametrically opposite. Mounted to slide in each keyway is a key 19, preferably rectangular in cross section, having an integral pin 20 projecting laterally therefrom above the depressed lateral surface. The member 13 has also diametrically opposite angular apertures 21 which will snugly engage the corresponding keys 19 when said openings are brought into alignment therewith; and the said openings align with the keyways when the lug 15 is in contact with the bridge 12, as shown in Fig. 4.

Mounted to turn on the depressed lateral surface of the driven member 10 is a ring 22 the outer diameter of which is substantially equal to the diameter of the flange 17

and that of the disk; that is to say, the lateral surfaces of the disk, ring and flange 17 are flush. The ring 22 has helically disposed slots 23 each of which is in engagement with a corresponding pin 20 of the key 19. By turning this ring or by arresting the movement of the ring while turning the driven member, the keys 19 can be moved in and out of engagement with the driving member 13. The said ring 22 has on the inner surface thereof a lug or abutment 24 which engages an elongated, arcuated, peripheral slot 25 provided on the depressed lateral surface of the driven member. This slot receives a resilient member 26 in the shape of a coil spring, one end of which abuts against one end of the slot 25, while the other end of the spring abuts against the abutment 24. Normally the spring 26 maintains the ring 22 in the position shown in Fig. 7, that is, it forces the keys 19 into engagement with the rectangular openings in the disk or driving member 13. To withdraw the keys from engagement with the driving member, that is, to uncouple the driving and driven members, the ring and pin must be displaced relatively, so as to bring the pins to the opposite ends of the slots, as shown in Fig. 7. The lateral displacement of the ring 22 on the driven member is prevented by the disk or driving member 13, which is, in turn, prevented from any lateral displacement by a washer and nut attached to the end of the magneto shaft 9 projecting out of the driven member.

Normally the driving and driven members are coupled together by the keys 19, and the coupling is unyielding that is, the driven member cannot lag behind the driving member no matter what the speed of the driven member is. As shown in the drawing, the driving member is provided with driving pins 27 whereby the same is connected to the driving shaft which is actuated by the engine shaft. But it is self-evident that the driving member 13 can be coupled in any suitable way to the driving shaft, actuated by the engine shaft. When the engine is to be started, by means of my attachment 29 the driving and driven members are uncoupled by means of a pawl 28 which is mounted to engage one of the projections 29 provided on the lateral surface of the ring.

The pawl 28 is preferably mounted to turn freely on a shaft 30 extending longitudinally of the magneto and bearing in lugs associated therewith. A spring 31 normally forces the pawl 28 toward the lateral surface of the attachment. The end of the shaft, adjacent the pawl, carries an arm 32 rigidly connected with the shaft and provided with a pin 33 adapted to engage the pawl when the arm is moved toward the pawl. The other end of the shaft 30 has a rigidly attached arm 34 which is connected

by a link 35 to an arm 36 in turn rigidly connected to the spark-controlling sleeve 37 of the magneto, whereby the spark is advanced or retarded by the standard means used therefor. When the engine is stopped, 70 the arm 36 is brought to a position which will permit the pawl 28 to come into engagement with one of the stops 29 of the ring 22; and as the engine is rotated, the driving member 13 will turn the driven member 75 while the ring 22 is arrested in its movement, causing the keys 19 to move out of engagement with the disk, thus unlocking the driving and driven members. A farther movement of the driven member will be 80 prevented by the pins 20 of the keys as the pins reach the other end of the helically disposed slots 23. Thus, the movement of the magneto shaft 9 will be arrested, while the driving member 13 will continue to rotate and the parting between the lug 15 and the bridge 12 will take place, causing a compression of the spring 16 within the annular slot 11 of the driven member 10. To give an accelerated movement to the 90 shaft of the magneto, the pawl 28 is disengaged from the stop 29 of the ring 22, thus permitting the expansion of the coil spring 16 which will force the driven member 10 and the magneto shaft 9 attached thereto to 95 overtake the driven member by forcing the bridge portion toward the lug 15. It is self-evident that the speed with which the driven member 10 and the shaft 9 will rotate will depend on the compression given 100 to the coil spring 16.

The pawl 28 is disengaged from the projection 29 of the ring by cam portions or bosses 38 formed on the edge of the disk, which cam portions are preferably in normal position of the attachment at right angles to the projections 29, so that the driving member will be forced substantially a quarter of a revolution ahead of the driven member before the same is released to overtake the driving member under the action of the spring 16. During the movement of the pin 20 within this slot 23, when the keys are withdrawn from engagement with the disks, that is, when the driving and driven members are uncoupled, the spring 26 will be compressed and remain so compressed until the expansion of the spring 16, which will bring in alignment the corresponding rectangular openings of the disk 120 with the keyways 18 of the driven member, when the said spring will be free to expand and, consequently, cause the ring to move relatively to the driven member, and thus force the keys into engagement with the 125 driving member and lock the same to the driven member. As soon as the spark sleeve control 37 is made to advance the spark, the same will cause the shaft 30 to rotate and therewith the arm 32, which will 130

prevent the pawl 28 from engaging the ring 22, consequently leaving the driving and driven members positively locked after the engine has started and the same continues 5 to work. The provision of the shaft 30 with its arms and its connection with the sleeve 37 prevents a person from starting the engine with an advance spark, and, consequently, prevents the back fire of the 10 engine in cranking or in starting the same. The pawl 28 is also provided with a pin 39 engaged in a slot 40 of a rod 41, by means of which rod the pawl can be moved away from my attachment independently of the 15 actuation of the sleeve 37.

From the above description and the drawings it will be noted that all parts of the attachment are so located that none of them can become lost or separated from either the 20 driving member or the driven member. As, for example, the keys are maintained in position in their keyway by the ring and the ring is prevented from lateral movement by the nut and washer which maintain the 25 driving member on the driven member. The abutment 24 is also prevented from displacement by the ring, and the same is placed into its groove by a cut-out 42 leading to the slot 25, to permit the placing of 30 said abutment thereinto. If desired, the device can be packed with grease. Very little attention will have to be paid to the same, as there are no parts which can get out of order or become loose.

35 From the foregoing description, taken in connection with the accompanying drawings, the advantage of the construction and operation of the attachment shown will be readily understood by those skilled in the 40 art to which the invention pertains; and while I have described the principle of operation, together with the attachment which I now consider to be the best embodiment thereof, I desire to have it understood that 45 the device shown is merely illustrative and that such changes may be made as are within the scope of the appended claims.

Having thus described my invention, I claim as new and desire to secure by Letters 50 Patent:

1. In a magneto attachment, a driving member; a driven member; means normally locking said driving and driven members; means for unlocking the driven member 55 from the driving member and arresting the movement of the same, whereby the driving member will run ahead of the driven member, said driving member having means for releasing said driven member after the 60 same has been displaced through a predetermined distance; means for forcing the driven member to overtake the driving member; and means for automatically locking the two when the driven member has 65 overtaken the driving member.

2. In a magneto attachment, a driving member; a driven member; means normally locking the two members; means for unlocking the driven member from the driving member and arresting its movement while 70 the driving member is free to turn; means for releasing said driven member after a predetermined displacement of the driving member; and means for causing the driven member to overtake the driving member 75 when the same is released, said locking means automatically coupling the two members when the driven member overtakes the driving member.

3. In a magneto attachment, a driving 80 member; a driven member; automatic coupling means unyieldingly connecting the driving member and the driven member; means for uncoupling the driven member from the driving member and arresting its 85 movement; means for releasing said driven member after a predetermined displacement of the driving member; and means for causing the driven member to overtake the driving member when the same is released, 90 whereby said coupling means automatically connects unyieldably the driving member and the driven member.

4. In a magneto attachment, a driving 95 member; a driven member; automatic coupling means unyieldably connecting the two members; means for uncoupling the driven member and arresting its movement; means for releasing said driven member after a predetermined displacement of the driving 100 member; and resilient means for causing the driven member to overtake the driving member when the same is released, whereby the coupling means automatically locks the driven member to the driving member. 105

5. In a magneto attachment, a driving member; a driven member; automatic coupling means unyieldably connecting the driving member and the driven member; means for uncoupling the driven member from the 110 driving member and arresting its movement; means for releasing said driven member after a predetermined displacement of the driving member and controllable by said driving member; and a spring for causing 115 the driven member to overtake the driving member when the same is released, whereby the coupling means automatically locks the driven member to the driving member.

6. In a magneto attachment, a driving 120 member; a driven member; automatic coupling means unyieldably connecting the driving member and the driven member; means for uncoupling the driven member from the driving member; means for arresting the movement of the driven member after it has been uncoupled, said driving member having means for releasing said driven member after a predetermined displacement of 125 the driving member; and a coil spring asso- 130

- ciated with the driving member and the driven member adapted to force the driven member to overtake the driving member after the release of same, said coupling means adapted to automatically establish unyielding connection between the driving member and the driven member when the driven member overtakes the driving member.
7. In a magneto attachment, a driving member; a driven member; automatic coupling means unyieldably connecting the driving member and the driven member; means for uncoupling the driven member from the driving member; means controlling the uncoupling means adapted to arrest the movement of the driven member; means associated with the driving member for operating said means controlling the uncoupling means, whereby the driven member is released after a predetermined displacement of the driving member; and a coil spring associated with the driving and the driven members adapted to force the driven member to overtake the driving member after the same has been released, said coupling means automatically establishing the unyielding connection between the driven member and the driving member when the driven member overtakes the driving member.
8. In combination with a magneto having a spark control, an attachment comprising a driven member rigidly connected to the magneto shaft; a driving member; automatic coupling means unyieldingly connecting the driving and driven members; means for uncoupling the driven member from the driving member and arresting its movement, said means being operated from the spark control of the magneto; means for releasing said driven member after a predetermined displacement of the driving member; and resilient means for forcing the driven member to overtake the driving member after the same has been released, whereby the coupling means will automatically and unyieldingly connect the driven member to the driving member.
9. In a magneto attachment, a driven member having an annular recess at one side thereof, said member having a portion bridging said annular recess; a driving member mounted to rotate on said driven member and having a lug projecting into said recess; a coil spring within said recess having one end thereof engaging the bridge portion and the other end, the lug of said driving member, whereby the lug normally contacts with the bridging portion; a key slidably mounted in said driven member and adapted to engage the driving member when the lug and bridge contact; a ring mounted to turn on said driven member but prevented from lateral movement thereon, said ring engaging said key; means for arrest-
ing the movement of the ring while the driving member is turned, whereby the key is withdrawn from engagement with the driving member, thereby permitting a relative movement between the driving and the driven members, thus causing a compression of the coil spring within the recess of the driven member, said driving member having means for engaging the means arresting the movement of the ring after a predetermined displacement of said driving member, whereby the compressed spring within the recess of the driven member causes the same to overtake the driving member by bringing the bridging portion against the lug of the driving member; and means associated with the ring for restoring the same to its normal position on the driven member, whereby the key is forced into engagement with the driving member.
10. In combination, a magneto having a spark control; means for driving the magneto; means coupling the magneto and drive; means controlling the coupling means, and in turn controlled by the spark control of the magneto.
11. In combination, a magneto having a spark control; means for driving the same; means coupling the magneto and drive unyieldingly; and means controlling the coupling means associated with the spark control of the magneto and adapted to become operative when the spark control is completely retarded.
12. In combination, a magneto having a spark control; driving means therefor; means locking the magneto to the drive; means for unlocking the magneto from the drive controllable from the spark control of the magneto; and means for automatically locking the drive and the magneto after the same has been unlocked controllable from the drive, substantially as and for the purpose set forth.
13. In a magneto attachment, a driving member; a driven member; means normally inoperative for yieldingly connecting the driving and the driven members whereby the driving member may be run ahead of the driven member; automatic coupling means unyieldingly connecting the two members normally; means for uncoupling the driven member from the driving member and for arresting the movement of the driven member, whereby the yielding connection becomes operative; and means for releasing said driven member after a predetermined displacement of the driving member, the yielding connection causing the driven member to overtake the driving member after the same has been released, whereby the coupling means automatically connects the driving and the driven members unyieldingly.
14. In a magneto attachment, a driving member; a driven member; yielding means

between said driving and driven members normally inoperative; automatic coupling means unyieldingly connecting the driving and driven members; means for uncoupling the driven member from the driving member and arresting the movement of the driven member; whereby the yielding means becomes operative; and means for releasing said driven member after a predetermined displacement of the driving member, whereby the yielding means causes the driven member to overtake the driving member, and when the same has overtaken the driving member the coupling means automatically connect the driven member and the driving member unyieldingly, rendering the yielding connection normally inoperative.

15. In a magneto attachment, a driven member having an annular recess at one side thereof; a portion bridging said annular recess; a driving member having a lug projecting into said recess; a coil spring within said recess having one end thereof engaging the bridging portion and the other end, the lug, whereby a yielding connection between the driving member and the driven member is formed; means normally locking the driving member and the driven member whereby the yielding connection is normally inoperative; means for unlocking the driven member from the driving member and arresting the movement of the driven member, whereby the coil spring is compressed; means for releasing the driven member controlled by the driving member whereby the coil spring causes the driven member to overtake the driving member; and means for automatically locking the driving member to the driven member when the same is overtaken.

40. 16. In a magneto attachment, a driven member having an annular recess at one side thereof; a portion bridging said annular recess; a driving member having a lug projecting into said recess; a coil spring within said recess normally maintaining the lug against the bridging portion; means locking the driving and driven members, whereby the coil spring is normally inoperative; means for unlocking the driven member from the driving member and arresting the movement of the driven member, whereby the coil spring is compressed and said lug is parted from the bridging portion, said driving member having means for releasing said driven member after a predetermined relative displacement of said driving member, whereby the coil will force the driven member to overtake the driving member by bringing the bridging portion against the lug; and resilient means associated with the driven member for automatically locking the driven member to the driving member when the coil spring has brought the bridging portion in contact with the lug of the driving member.

45. 17. In a magneto attachment, a driven member having an annular recess at one side thereof; a portion bridging said annular recess; a driving member having a lug engaging said recess; a coil spring within said recess maintaining the lug against the bridging portion; keys slidably mounted in said driven member, said driving member having means adapted to engage the keys whereby the same is locked to the driven member; a ring mounted to turn on the driven member to prevent from lateral displacement thereon said ring engaging said keys; resilient means tending to maintain said ring in a predetermined position on said driven member whereby the keys are maintained in engagement with the driving member; and means for arresting the movement of the ring while the driving member is turned, whereby the keys are withdrawn from engagement with the driving member, permitting a relative movement between the driving and the driven members, thus causing compression of the coil spring within the recess of the driven member by the parting of the lug from the bridging portion, said driving member having means for engaging the means arresting the movement of the ring after a predetermined displacement of said driving member, whereby the coil spring within the recess of the driven member causes the same to overtake the driving member and brings the bridging portion against the lug of the driving member, said resilient means automatically restoring the ring to its normal position on said driven member and thus shifting the keys into engagement with the driving member.

50. 18. In a magneto attachment, a driving member, a driven member, sliding keys carried by the driven member, openings in the driving member to receive said keys, projections on said keys, a ring carried on the periphery of the driven member and having diagonally arranged slots to receive said key projections, means for arresting the movement of said ring whereby the said keys are withdrawn from the openings in said driving member permitting it to move forward away from the ring and the driven member, means for releasing the ring after a predetermined displacement of the driving member and means carried within said members to cause the driven member to move rapidly forward to its normal position, and means carried by the driven member to cause said ring and keys to return to their normal positions for the purpose described.

55. 19. In a magneto attachment, a driven member having an annular recess at one side thereof, a bridge across said recess, a driving member having a lug projecting into said recess, a coil spring within said recess, one end abutting against the bridge, the other against said lug, keys carried by the

125

130

driven member and normally in engagement with the driving member, a ring movably carried by the driven member and adapted to control the movement of said 5 keys and driven member, means for arresting the movement of said ring whereby the keys are withdrawn from engagement with the driving member permitting it to move forward away from the ring and driven 10 member to compress said coil spring, by means of said lug, means for releasing the ring and driven member after a predetermined displacement of the driving member whereby the coil spring will move the 15 driven member rapidly forward to its normal position, and resilient means carried by the driven member to cause said ring to return to its normal position whereby said keys engage with the driving member for the purpose described.

20. In a magneto attachment, a driving member; a driven member; automatic coupling means unyieldingly connecting the driving member and the driven member; 25 means for uncoupling the driven member from the driving member and arresting its movement; means for releasing said driven member after a predetermined displacement of the driving member; and means for causing 30 the driven member to overtake the driving member when the same is released.

21. In a magneto attachment, a driving member; a driven member; automatic coupling means unyieldably connecting the two 35 members; means for uncoupling the driven member and arresting its movement; means for releasing said driven member after a predetermined displacement of the driving member; and resilient means for causing the 40 driven member to overtake the driving member when the same is released.

22. A starting coupling for igniter magnetos comprising co-axial, relatively rotatable driving and driven members, a lock 45 normally connecting said members to positively hold the same against relative rotation, an actuating spring interposed between said members, a trip arranged to successively release said lock and arrest said driven member to thereby place said spring under tension and means for automatically shifting said trip to thereby release said driven member.

23. A starting coupling for igniter magnetos comprising co-axial, relatively rotary driving and driven members having a co-operating lug and stop, a spring interposed between said members, a spring-held locking dog on said driven member and normally 55 engaging said driving member to normally hold the same positively against relative rotation with said lug and stop in engagement, a shiftable trip arranged to successively release said lock dog and arrest said driven 60 member to thereby place said spring under

tension, and a cam lug on said driving member for shifting said trip to thereby release said driven member.

24. In a starting coupling for igniter magnetos, the combination with a magneto shaft 70 and a stationary part, of co-axial, relatively rotatable driving and driven members for rotating said shaft, means positively connecting said members against relative rotation, an actuating spring interposed between 75 said members for imparting an accelerated rotary movement to said driven member, and a trip device mounted on said stationary part and arranged to successively release said positively connected members and arrest 80 said driven member to thereby place said spring under tension, and means on said driving member for automatically shifting said trip to thereby release said driven member and permit the accelerated rotation 85 thereof by said actuating spring.

25. The combination with a driven member, secured to the rotatable part of an electric current generator, a driving member rotatably mounted thereon, and a spring 90 set between so as to be tensioned by rotating the driving member in advance of the driven member, of a coupling device permanently engaging with the driven member, means for engaging a part of the coupling device for stopping its rotary motion as well as the rotary motion of the driven member to tension said spring and means operated by the driving member when the driving member is rotated to a predetermined point in advance of the driven member for releasing the coupling device from said stopping means to allow said spring to impact its stored energy to the driven member and means for holding the coupling device in engagement with the driving member 100 while the generator is driven at or above its normal speed.

26. An impulse starting coupling for igniter magnetos comprising, a driving 110 member, a driven member, means for holding said driven member from rotation during a partial rotation of said driving member, a spring put under tension by the rotation of the driving member and non-rotation of the driven member, means for automatically releasing said driven member after a predetermined displacement of the driving member, whereby said spring will cause the driven member to overtake the 120 driving member, and means for coupling the driving and driven members unyieldingly together after said release has occurred.

27. An impulse starting coupling for an 125 electric current generator comprising, a driven member adapted to be fastened to the rotating part of the generator, a driving member rotatably mounted on the driven member, a device for coupling the driving 130

- and driven members together to prevent deviation in the timing of the generator with respect to the engine driving it during running thereof, means for uncoupling the 5 driving and driven members when the impulse coupling is brought into starting position whereby the driven member is held from rotation and the driving member is caused to advance ahead of it, a resilient 10 member interposed between the driving and driven members and adapted to be put under tension by the said advance of the driving member, means for automatically releasing the driven member at a predetermined point 15 of rotation of the driving member whereby said resilient member causes the driven member to take a sudden impulse forward to produce an augmented flow of current from the generator for the purpose de- 20 scribed.
28. An impulse starting coupling for an electric current generator comprising, a driven member adapted to be fastened to the rotating part of the generator, a driving member rotatably mounted on the driven member; coupling means carried on the driven member, for fastening the driving and driven members together to prevent deviation in the timing of the generator with 25
- respect to the engine driving it during running thereof, but adapted to be acted on for unfastening the driving and driven members when the impulse coupling is brought into starting position whereby the driven member is held from rotation and the driving member is caused to advance ahead of it; a resilient member interposed between the driving and driven members and adapted to be put under tension by the said advance of the driving member, means for automatically releasing the driven member at a predetermined point of rotation of the driving member whereby said resilient member causes the driven member to take a sudden impulse forward to produce an augmented flow of current from the generator for the purpose described, and means associated with the coupling means for moving and holding the same into engagement with the driving member after said release has occurred. 30
